UNITED STATES PATENT OFFICE.

WALTER JAMES DONNE, OF LONDON, ENGLAND.

DESIGN FOR A GAME-BOARD.

52,210.

Specification for Design.

Patented July 23, 1918.

Application filed November 27, 1916. Serial No. 133,802. Term of patent 7 years.

To all whom it may concern:

Be it known that I, WALTER JAMES DONNE, a subject of the King of Great Britain, residing at London, England, have invented a new, original, and ornamental Design for a Game-Board, of which the following is a specification, reference being had to the accompanying drawing, forming a part thereof.

I claim as my invention:

The ornamental design for a game board as shown.

WALTER JAMES DONNE.
